Specification of Letters Patent. Patented July 7, 1914.

Application filed January 24, 1912. Serial No. 272,137.

To all whom it may concern:

Be it known that we, PAUL E. GOLDMANN and ALBERT F. DAUM, citizens of the United States of America, residing at Pittsburgh, 5 in the county of Allegheny and State of Pennsylvania, have invented certain new and useful Improvements in Fuses, of which the following is a specification, reference being had therein to the accompanying drawings.

Our invention relates to improvement in fuses and more particularly to structures capable of being refilled.

Among the objects of our invention are— 15 (1) to provide a structure in which the fuse element may act as a retaining device for plugs prior to the placing of the end cap in position; (2) to provide a structure in which the seating of the end cap acts to provide a 20 wiping contact with the fuse element; (3) to provide a structure in which the fuse element is held in contact with the end cap regardless of the expansion and contraction 25 of the shell carrying the fuse; (4) to provide a structure in which metallic contact other than that provided by the fuse element is substantially eliminated; (5) to provide a structure in which it is substantially 30 impossible to provide a cutting off of the fuse at the point of contact.

Further objects are to provide a structure which is simple and efficient in operation, employs a minimum number of parts, which can be readily refilled, and which can be 35 manufactured and installed at a relatively low cost.

To these and other ends, the nature of which will be readily understood as the invention is hereinafter disclosed, our invention 40 consists in the improved construction and combination of parts hereinafter fully described, illustrated in the accompanying drawings and particularly pointed out in the appended claims.

45 In the accompanying drawings in which similar reference characters indicate similar parts in each of the views—Figure 1 is a central longitudinal sectional view taken through one form of our fuse, one of the 50 plugs being shown in elevation. Fig. 2 is an end view of the fuse with the cap removed. Fig. 3 is a side elevation of one of the plugs. Fig. 4 is a perspective view of the same. Fig. 5 is a longitudinal sectional

view of one of the plugs, the section being 55 taken through one of the slots. Fig. 6 is a longitudinal sectional view taken at right angles to the direction of length of the kerf. Fig. 7 is a longitudinal sectional view of a modified form of plug. 60

The fuse carrier or cartridge forming the subject matter of our present invention comprises a tubular member 10, preferably of insulating material, such as fiber, glass, or other material, said member being preferably screw-threaded exteriorly at its ends, and being relatively smooth interiorly throughout its length. 65

11 designates an end plug, two of which are preferably employed, being substantial 70 duplicates. The preferred form of plug is that shown in Figs. 1 to 6 inclusive, in which each plug has its inner end somewhat cone-shaped, and provided with radial slits 12, extending from the rear to the opposite end 75 of the cone-shaped portion, these slits serving to divide this portion into parts which, under pressure, may yield slightly inwardly to place the plug under a slight tension, the member 10 preferably having its ends 80 slightly reamed out to permit a closer fit at this point, although this is not absolutely necessary, the purpose of which will presently appear. The remaining portion of the plug is preferably tapered in the opposite direction, as at 18, and is provided intermediate the ends of such tapered portion with an annular groove 14 of less depth 85 than the normal thickness of the fuse wire to be employed in connection with the fuse, 90 said plug is also provided with an axial opening 15, and with a kerf which extends diametrically of the plug and leads inwardly from the outer end thereof to a point in proximity to the inner wall of the 95 groove 14.

17 designates an end cap which has an interior configuration approximating that of the tapered portion of the plug, with the exception of the groove and kerf, said cap 100 being interiorly screw-threaded, as at 18, to permit it to be secured to the threaded portion of the member or shell 10, the parts being preferably arranged so that when the end cap is in position, the interior tapered 105 wall of the cap will be spaced from the tapered exterior of the plug to present a metallic contact between the plug and cap.

The fuse is assembled by placing a plug at each end of the member or shell 10, passing the fuse wire 20 of proper size through the axial openings of the plugs and carrying the free ends of the wire radially through one of the parts of the kerf 16, and into the groove 14 around which it is carried, as indicated in Fig. 2. As the groove is of less depth than the thickness of the wire, it will be readily understood that a portion of the latter projects beyond the plane of the tapered wall of a plug, with the result that when the cap is threaded to position its taper interiorly contacts with the exposed portion of the fuse wire, and provides a wiping contact therewith, insuring a perfect contact between the fuse wire and the cap; inasmuch as the fuse wire lies within the groove 14, it will be readily understood that this movement of the end cap will not cause the fuse wire to be cut off, nor will it change the position of the fuse wire with respect to the position it occupies between the plug and end cap, insuring that the threading of an end cap will not place any material strain on the fuse wire between the plugs in either direction. In fact, the provision of the slotted conical inner end so as to practically provide fingers will enable the plug to yield slightly inwardly under the threading movement of the cap, the tension thus provided tending to retain the fuse wire in contact with the cap. Should the material of the member 10 contract and expand under changes in temperature, the wiping contact will still be retained by reason of the tendency of a plug to move outwardly under the tension provided by its inner end, the plug moving in this manner in one direction under contraction of the member and in the opposite direction under its expansion, the plug serving substantially as a compensating device for the contraction and expansion of the member.

In the form shown in Fig. 7, the compensating structure is omitted, the inner end of the plug in this form being adapted to loosely fit within the tubular member, and having a peripheral flange, 19, which is adapted to abut against the end of the member 10. In this form, the wiping contact is obtained, together with the advantage of the groove and the kerf structure, the compensating feature, however, being omitted. By this particular arrangement, it will be readily understood that the shell, plugs and fuse wire may be assembled and retained in position regardless of the presence of the end cap, thereby making the device one which is readily assembled and which cannot readily be affected by handling, unless deliberate attempt is made to affect the assembled parts. And inasmuch as there is no intention to thread the cap to a position where metallic contact is had between the plug and end cap, and especially in the preferred form where

the yielding of the fingers will permit the plug to slightly yield under such pressure, liability of fusing of these metallic parts when the fuse is blown is eliminated. Furthermore, by reason of the particular mounting of the plug within the shell, it will be readily understood that no difficulty will be had in removing the parts for the purpose of refilling the fuse or renewing the fuse wire. Another advantage lies in the presence of the kerf 16, which offers in connection with the longitudinal opening, an additional space to take care of the effect of the blowing of the fuse, thereby tending to prevent explosion of the cartridge when the fuse wire blows.

The several parts forming the invention are such as can be readily manufactured at a relatively low cost, and provide for an easy assemblage and renewal.

While we have herein shown and described one or more ways in which our invention may be provided, it will be readily understood that changes and modifications therein may be required or desired to meet the exigencies of use, and we desire it to be understood that we reserve the right to make any and all such changes and modifications as may fall within the spirit and scope of the invention as expressed in the accompanying claims.

Having thus described our invention, what we claim as new is:

1. In a refillable fuse, a shell, a plug seated at an end of said shell, said plug having a tapered forward portion formed with an annular groove, a passage-way through said plug and leading laterally to afford passage for a fuse element therethrough into said groove, and a cap adapted to be secured directly to said shell and having an internal configuration to provide a wiping contact with the element when the latter is in position within the groove, the depth of the groove preventing severance of the element during its change in cross-sectional configuration provided by the wiping action.
2. In a refillable fuse, a shell of insulating material, a plug seated within the end of the shell, said plug having an axial passage-way leading therethrough and also provided with a radial recess leading inwardly from the forward end of the plug, said plug having an annular groove intersecting said recess in advance of its inner end, and a cap adapted to be secured directly to said shell and having a configuration to provide a wiping contact with a fuse element extending through said passage-way and into said groove, the depth of the groove preventing a severance of the element during its change in cross-sectional configuration provided by the wiping action.
3. In a refillable fuse a shell, a plug carried by said shell and having its forward

end tapered, said plug having an axial passageway to accommodate a fusible element and also having a peripheral groove to receive said fuse element, and an end cap 5 adapted to be secured directly to the shell and being formed to provide a wiping contact with the fuse element, the depth of said groove preventing severing of the fuse element during its change in cross-sectional 10 configuration provided by the making of such contact.

4. A plug for fuse cartridges comprising a metallic member having an axial opening and having its inner end tapered inwardly, 15 said tapered portion being slotted longitudinally.

5. A plug for fuse cartridges comprising a member having an axial opening and having its exterior tapered toward its ends in

opposite directions, the inner tapered portion being slotted longitudinally, the outer tapered portion having a diametrical kerf intersecting the axial opening, and also having a peripheral groove intersecting the kerf. 20

6. A plug for fuse cartridges comprising a member having an axial opening and having its exterior tapered toward its ends in opposite directions, the inner tapered portion being slotted longitudinally, the outer tapered portion having a diametrical kerf 25 intersecting the axial opening.

In testimony whereof we affix our signatures in the presence of two witnesses.

PAUL E. GOLDMANN.
